BURN BATH TABLE

Neal Owens, New Orleans, La., and Raymond L. Jewell, Erie, Pa., assignors to American Sterilizer Company, Erie, Pa.

Application October 11, 1944, Serial No. 558,160

7 Claims. (Cl. 311—7)

1

This invention relates to a surgical table, and more particularly, to a burn bath table for supporting patients while they are being treated for burns, although it will be understood that this table can be used for any type of trauma.

An object of the invention is to provide a simple, comparatively light weight burn bath table which will support the patient with the minimum area of supporting surface in contact with the patient.

Another object of the invention is to provide an adjustable burn bath table which enables the physician to treat burns by the newly developed soap and water system wherein pure soap and sterile water are gently flushed over the burns. Inasmuch as there is a comparatively large amount of fluid used and it is essential that the fluid drain from the wound, a table which will properly hold the patient while permitting this form of treatment to be performed is of great advantage.

Another object of the invention is to provide a readily movable table with adjustable wings or auxiliary frames for holding the arms and legs of the patient while his body is supported in a horizontal position on a comparatively narrow band of fabric, which is preferably composed of a nylon strip.

A still further object is to construct a table whereby all drainage from the flushing liquids used and any bleeding will be caught and discharged into a central trough where the liquids are led off for disposal.

In making up such a surgical table the present design is such that the major portions thereof can be readily fabricated from simple pipe sections brazed or otherwise connected together. The auxiliary radially extending arm and leg holders are so connected to the main frame of the table that they may be readily pivoted for movement in a horizontal plane and thus adjusted to suit the patient's stature. When the burn bath table is not in use the auxiliary arm and leg holders are adapted to be pivoted or folded over the table body thereby reducing the overall dimensions of the apparatus and permitting the table to be stored in a space of approximately the size of the frame per se.

In the drawings:

Fig. 1 is a front elevation view of the burn bath table illustrating the component parts thereof with a representation of a patient positioned thereon:

Fig. 2 is a top plan of the burn bath bed showing the normal relationship of the several mem-

2

ber supporting stands and associated liquid catch pans; and

Fig. 3 is an end elevational view of the burn bath table.

Essentially the present surgical table consists of an elevated horizontal, rectangular frame having longitudinal sides 1 and end bars 3 supported on vertical posts 5 provided with supporting floor engaging caster wheels 7. An arcuate, centrally arranged, upstanding post 9 having a bifurcated lower end 11 is attached to the end bar 3 of the elongated horizontal frame and to a second end cross stretcher 13 with the upper end of the post terminating above the horizontal plane of the main frame. A central vertical post 15 of a length approximately the same as the front post 9 is secured to the opposite end bar 3 and is fitted with a detachable horizontal roller 17. The vertical post 9 is provided with a horizontal take-up roller 19 mounted on an axle 21 mounted in offset detachable bracket 23 having its lower end 25 positioned in the upper end of post 9. The axle 21 and the take-up roller 19 are adapted to be rotated by cross handle 27 and held in fixed position by the ratchet and pawl device 29.

The patient is placed on the flat body supporting band 31 of suitable textile material, preferably nylon, carried by rollers 17 and 19 with the free ends leading to the take-up roller 19 whereby the position and tautness of the body supporting band may be regulated by operation of the ratchet and pawl device 29. As illustrated in Fig. 1, the patient is placed on the longitudinal nylon band 31 which is comparatively narrow in width so as to reduce the area in surface contact with the patient to a minimum.

The patient's arms and legs are further supported and made accessible for treatment by four member holding auxiliary tables or wings 35 pivoted to the main frame. Two of the wings are placed adjacent the foot of the main horizontal frame at the opposite corners thereof and the other two are pivotally secured at the sides of the main frame. The four auxiliary tables are all similar in construction with the two oppositely positioned wings or frames 35 for holding the patient's arms mounted in the upper ends of the arcuate upwardly extending posts 37 secured at their lower ends to the longitudinal sides 1 of the frame. Each member holding wing 35 consists of a horizontal elongated basin 39 having an integral transverse and integral bottom web 41 on the under side thereof with a supporting socket 43 formed at the point of intersection of the web

and fitted over the upper end of the posts 37. The sides and outer end edge of the elongated basins 39 extend upwardly and outwardly into a flange 45 and the parallel side edges of the basin form a track or retainer for an adjustable member supporting frame 47. These frames have spaced apart upright arms 49 joined by cross rods 51 with the lower ends of the arms secured to the screw clamps 53 which cooperate with the side flanges 45, and thus the frames, by operation of the screw clamps, may be positioned at any point along the side flanges 45 of the elongated basins. The arm holding means for these frames may take the form of a comparatively narrow fabric strip 55, preferably of nylon, secured around the ends of the horizontal rods 57 affixed through the upper ends of the spaced vertical arms 49.

The inner end portions 59 of the elongated basins 39 are not flanged and are cut away to form a discharge mouth for any liquid falling into the basin and the basins are so constructed that their bottoms slope and the liquid runs off them by gravity. It will be observed that all four basins 39 discharge into a large elongated basin or trough 61 overlying the main rectangular frame of the table and underlying the horizontal planes of the patient supporting band 31. Consequently, when the patient is washed the wash liquid and any bleeding is caught by the basins 39 and drained into bottom trough 61. The elongated trough 61 may be held in detachable position by sockets 65 attached to the under side of the trough and cooperating with vertical extensions 63 on the main frame. A suitable drain outlet 67 leading to a pail or sewer connection is provided for the trough 61.

The auxiliary holders including the respective drain basins may be pivoted or folded longitudinally or over the table whereby the apparatus can be conveniently stored and the overall space occupied thereby is reduced to substantially that of the frame proper.

We claim:

1. A surgical table of the character described having a floor supported frame, vertical risers secured to the ends of the frame and a horizontal body supporting strip secured to the vertical risers, auxiliary arm and leg supporting means mounted on the frame, a liquid trough positioned on the frame below the body supporting strip, and elongated basins carried by the arm and leg supporting means arranged to discharge into the said trough.

2. A surgical table of the character described having a floor supported rectangular frame, vertical risers secured to the ends of the frame and a narrow horizontal body supporting strip secured to the vertical risers, auxiliary arm and leg supporting frames pivoted intermediate the length 60 of the sides and at the corners of one end of the rectangular frame, a liquid trough positioned on the rectangular frame below the body supporting strip, and elongated basins carried by the auxiliary arm and leg supporting frames arranged 65 to discharge into the said trough.

3. A surgical table as defined in claim 2 wherein the auxiliary arm and leg supporting frames include spaced vertical posts adjustably secured to the sides of the said elongated basins with fabric strips carried between the said posts on which the arms and legs are adapted to rest.

4. A burn bath apparatus comprising an elongated floor supported frame, vertical risers respectively secured centrally of the opposite ends 10 of the frame and extending above the upper plane of the frame, a horizontal body supporting strip of fabric having its opposite ends attached to the upper ends of said risers, auxiliary arm and leg supporting frames pivoted intermediate the sides and at oppositely disposed points at one end of said frame, and a fabric strip secured transversely across the top of each of said auxiliary frames, said auxiliary frames and the fabric strips secured thereto being constructed and arranged to support the arms and legs in the same approximate plane as the body supporting strip.

5. A burn bath apparatus as defined in claim 4 wherein a liquid receiving trough is positioned on the elongated frame and liquid receiving basins 25 are positioned on the auxiliary arm and leg supporting frames in such a manner as to discharge into the said liquid receiving trough.

6. A burn bath table comprising, in combination, an elevated horizontal frame, a liquid receiving 30 trough supported on said frame, central end posts secured to the frame and extending vertically above the horizontal plane thereof, a horizontally and relatively narrow fabric body supporting strip secured between the upper ends of the vertically extending post, said strip being free from other support between said posts and auxiliary 35 frames pivoted on opposite sides of the horizontal frame, each of said auxiliary frames being provided with a member-supporting fabric strip lying in substantially the same horizontal plane 40 as said body supporting strip.

7. A burn bath table as defined in claim 6 wherein in the auxiliary frames are pivoted adjacent the corners of one end of the horizontal frame and 45 to the opposite sides of the frame in proximity to the opposite end thereof.
